UNITED STATES PATENT OFFICE.

GEORGE A. ENSIGN, OF DEFIANCE, OHIO, ASSIGNOR TO DEFIANCE MACHINE WORKS, OF DEFIANCE, OHIO.

BORING AND REAMING MACHINE.

SPECIFICATION forming part of Letters Patent No. 726,662, dated April 28, 1903.

Application filed November 17, 1902. Serial No. 131,666. (No model.)

To all whom it may concern:

Be it known that I, GEORGE A. ENSIGN, a citizen of the United States, and a resident of Defiance, in the county of Defiance and State 5 of Ohio, have invented a new and Improved Boring and Reaming Machine, of which the following is a full, clear, and exact description.

The object of the invention is to provide a new and improved boring and reaming machine arranged to permit convenient, quick, and accurate shifting of the work-holder, to allow of first boring the work and then reaming it without removing the work from the work-holder, and insure the formation of an 15 accurate hole.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the views.

25 Figure 1 is a perspective view of the improvement as arranged for boring and reaming heavy work. Fig. 2 is a plan view of the same, the parts being in position for boring. Fig. 3 is a transverse section of the same on 30 the line 3 3 of Fig. 2. Fig. 4 is a similar view of the same, showing the work-holder in position for reaming. Fig. 5 is a plan view of part of the improvement, showing the work-holder for light work. Fig. 6 is a front elevation of the same, and Fig. 7 is an end view 35 of the same.

A head-stock A, secured to a bed B, is provided with suitable bearings for parallel longitudinally-extending spindles C and D, carrying pulleys E and E', respectively, connected by belts with other machinery for imparting a continuous rotary motion to the said spindles. The spindle C carries at its forward end a chuck or like tool-holder C' 40 for a tool F, and a chuck D' is on the forward end of the spindle D and carries a reamer G, designed for reaming a hole H, bored by the boring-tool F in the work H, held on a work-holder I.

45 The work-holder I (shown in Figs. 1, 2, 3, and 4) consists, essentially, of a pair of self-

centering V-shaped jaws J and J', mounted to slide toward or from each other on suitable guideways formed vertically on a bracket K, bolted or otherwise secured to the top of 55 a slide L, mounted to slide transversely on a guideway N', formed on a carriage N, having longitudinal movement on the guideway B' of the bed B. The jaws J and J' are simultaneously moved toward or from each other 60 to clamp or disengage the work H, and for this purpose a screw-rod J² is provided, mounted to turn in a suitable bearing K', (see Figs. 3 and 4,) formed on the bracket K, and the said screw-rod J² has right and left 65 hand threads screwing in the jaws J and J', so that on turning the screw-rod the jaws are caused to slide toward and from each other, according to the direction in which the screw-rod J² is turned. A handle J³ in the shape 70 of a handled wheel is secured on the upper end of the screw-rod J² to permit the operator to conveniently turn the screw-rod for the purpose above described.

In order to bring the work H into the 75 proper longitudinal position on the jaws J and J', a stop J⁴ is provided, mounted to slide on a rod J⁵, bolted or otherwise secured to the forward end of the jaw J', and the said stop J⁴ after the desired adjustment is made 80 is secured in place on the rod J⁵ by a suitable set-screw J⁶.

When the jaws J and J' are in an open position, then the operator places the work H in position on the lower jaw J' and moves the 85 work forward until its front end abuts against the stop J⁴, and then the operator turns the handle J³ to move the jaws J and J' toward each other, so that the work is clamped and self-centered in the jaws J and J'. 90

A slide L is provided at its front and rear ends with adjustable stops L' and L'', preferably in the form of screw-rods, as plainly indicated in Figs. 3 and 4, the inner ends of the stops being adapted to abut against lugs N² 95 and N³, respectively, formed or secured on the top of the carriage N. The stops L' and L'' are made adjustable to compensate for any wear of the stops and the lugs N² N³, against which the stops abut, so that the slide is 100 moved into the correct position to bring the longitudinal center of the jaws J J' and the

work therein into exact alinement with the boring-tool F and reamer G to allow accurate boring of the hole and exact reaming thereof. It will also be seen that in case it is desired to bore in the work a hole eccentrically relative to the longitudinal center of the jaws J J' then the stops L' and L² are correspondingly adjusted to bring the work into the desired position relative to the boring-tool and the reamer.

When it is desired to bore a hole in the work H by the boring-tool F, then the slide L is moved into the position shown in Fig. 3—that is, until the stop L² abuts against the lug N³—and when it is desired to ream the hole H', bored in the work H by the boring-tool F, then the operator moves the slide L transversely into the position shown in Fig. 4—that is, until the stop L' abuts against the lug N². When the slide L is in this position, the hole H' in the work is in axial alinement with the reamer G, so that the latter can ream the hole on the forward movement of the tool-holder.

The bracket K is provided with an opening K² for the passage of the reamer G at the time the slide L is in the position shown in Fig. 3 and the hole is bored by the boring-tool F in the work H.

In order to impart a longitudinal sliding motion to the carriage N and the parts supported thereon, the following device is provided: On one side of the bed B is secured a rack O, in mesh with a pinion O', secured on the inner end of a transversely-extending shaft O², journaled in a bearing N⁴, attached to the carriage N. On the outer end of the shaft O² is secured a hand-wheel O³ under the control of the operator for imparting a turning motion to the shaft O², so as to cause the pinion O' to roll over on the rack O, so that a forward or backward sliding motion is given to the carriage N—that is, according to the direction in which the hand-wheel O³ is turned. The forward sliding motion of the carriage N is limited by stops P, held longitudinally adjustable in a bracket P', secured to the bed B at the inner end of the guideway B'.

The operation is as follows: When the work H is secured between the jaws J and J', as above described, and the slide L is in the position shown in Fig. 3, then the operator turns the hand-wheel O³, so as to feed the carriage N inward, and thereby bring the work H to the boring-tool F for the latter to bore the hole H' centrally in the work H. When the carriage N abuts against the stops P, then the hole H' is bored through the work H and then the operator turns the hand-wheel O³ in a reverse direction, so as to run the carriage N back to its starting position. The operator then pushes the slide L transversely until the stop L' abuts against the lug N², (see Fig. 4,) and again turns the hand-wheel O³, so as to feed the carriage N inwardly to bring the work H to the reamer

G, which now reams the hole H' previously bored by the boring-tool F. The hole is completely reamed at the time the carriage N reaches the stops P, and then the operator turns the hand-wheel O³ in a reverse direction to move the carriage N and the parts thereon back to an outermost position. The operator now turns the hand-wheel J³, so as to open the jaws J and J' to allow of removing the work H and of substituting a new piece, after which the hand-wheel J³ is turned in the opposite direction to close the jaws J and J' to securely clamp the work in position. The operator now turns the slide L back to its original position (shown in Fig. 3) and then feeds the carriage N forward by turning the hand-wheel O³ to bore the hole H' in the work by the boring-tool F. The above-described operation is then repeated. A brush Q, held on a suitable stand Q', attached to the slide L, is connected by a hose Q² with a suitable water-supply Q³, and this brush Q stands in the path of the boring-tool F and the reamer G, according to the position of the slide L, so as to keep the said boring-tool F and the reamer G always in a cool condition.

It is understood that the tool-holder I, having the self-centering clamping-jaws J and J', is used only for heavy work; but when it is desired to bore and ream holes in light work then the tool-holder shown in Figs. 5, 6, and 7 is employed.

On the slide L, in place of the bracket K, is secured a plate R, having in its top a longitudinally-extending V-shaped groove or self-centering jaw R' for the work to rest in, and above the said jaw is located a clamp S for engaging the top of the work H to clamp it in place on the jaw R'. The clamp S is preferably in the shape of a disk, mounted eccentrically on a stud S', secured in a bracket R², extending upwardly from the rear side of the jaw R', and the said disk is provided with a handle S², adapted to be taken hold of by the operator for imparting a turning motion to the disk S, so as to move the same with its peripheral face in or out of contact with the top of the work H to clamp the latter in the jaw R' or to release the work after the hole is bored and reamed.

In order to impart a quick sliding motion to the carriage N, the bracket N⁴, with its shaft O², pinion O', and hand-wheel O³, is removed from the carriage N, and instead of this mechanism a hand-lever T is employed, engaging a loop N⁵ on the carriage, the lever being fulcrumed at its rear end on a pivot T', removably secured in a socket T² by a set-screw T³, the socket being formed on the top of a support T⁴, preferably made in sections bolted together and adjustably held on a guideway U, extending longitudinally on the rear side of the bed B. The guideway U is provided with heads U', engaging the outer ends of rods U² and fastened thereto by set-screws U³, and the said rods U² are held to slide transversely in bearings B³, extending from the rear side

- of the bed B. Set-screws B⁴ serve to fasten the rods U² in place in the bearings B³. (See Figs. 3 and 4.) Now by the arrangement described it is only necessary for the operator 5 to impart a swinging motion to the lever T to move the carriage quickly inwardly for boring and reaming the hole, as previously described, or to move the carriage back again into an outermost position. The support T⁴, 10 on which the lever T is fulcrumed, is adjustably secured on the longitudinal guideway U to permit of bringing the carriage N nearer to or farther from the boring-tool F and reamer G, according to the length of the work 15 under treatment—that is, if the work is short the carriage is moved nearer to the boring-tool and the reamer—and the support T⁴ is correspondingly adjusted on the guideway U—that is, moved nearer to the head-stock—and then 20 secured in place on the support, and if the work is long the carriage is moved outward and the support correspondingly adjusted on the support U, so that the lever T is always in proper position relative to the carriage N. 25 The guideway U is held transversely adjustable to allow the use of a long lever T in case the work is of considerable length, and it requires a long sweep of the lever T to feed the carriage the desired distance. It is understood 30 that it is very desirable to have the handle end of the lever T always stand within convenient reach of the operator, and this position of the lever is readily obtained by adjusting the support T⁴ longitudinally on 35 the guideway U and the latter transversely on the rods U², attached to the bed B. It is understood that the slide L is shifted, as previously explained, to bring the work into boring or reaming position. 40 Having thus described my invention, I claim as new and desire to secure by Letters Patent—
  1. A boring and reaming machine having a work-holding carriage and a feeding device for the carriage, the feeding device comprising a transversely-adjustable guideway extending in the direction of the movement of the said carriage, a pivot lengthwise adjustable on the said guideway and a hand-lever connected with carriage and fulcrumed on 45 said pivot, as set forth.
  2. A machine of the class described provided with a work-holder comprising a vertically-disposed bracket, a pair of self-centering jaws mounted to slide toward and from 50 each other on the said bracket, a screw-rod for opening and closing the said jaws, a rod extending from the forward end of the lowermost jaw and a stop held lengthwise adjustable on the said rod, and arranged to engage 55 the end of the work, as set forth.
  3. A machine of the class described having a bed provided with a guideway, a carriage mounted to slide thereon, a second guideway parallel to the said bed-guideway and trans- 60 versely adjustable thereto, a pivot lengthwise adjustable on the said second guideway, and a lever fulcrumed on the said pivot and engaging the said carriage, to move the latter forward and backward on the bed-guide- 65 way, as set forth.
  4. A machine of the class described provided with a feeding device for the carriage, comprising a transversely-adjustable guideway extending lengthwise in the direction of the movement of the carriage, a pivot lengthwise adjustable on the guideway, and a lever fulcrumed on the pivot and connected with the carriage, to move the latter forward or 70 backward, as set forth.

In testimony whereof I have signed my name to this specification in the presence of two subscribing witnesses.

GEORGE A. ENSIGN.
